UNITED STATES PATENT OFFICE.

AUTHUR F. PYM, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON SHOES.

Application filed June 3, 1921. Serial No. 474,701.

This invention relates to shoe machinery, and is illustrated as embodied in an apparatus for operating on the insides of shoes.

In making turned shoes with sewed heel seats, the lining is not sewed in at the bottom around the heel seat, but is attached by adhesive after the shoe has been turned, a shank piece being thereafter inserted to cover the margin of the lining at the heel seat, and to extend forward approximately to the ball line. So far as I am aware, these various operations of securing the lining and shank piece in place have always been performed by hand, the adhesive being applied by a brush, the lining "laid" or smoothed against the adhesive by the fingers of the operator, and a shank piece thereafter inserted in the shoe.

An object of the invention, accordingly, is to improve the making of turned shoes by providing mechanical means to perform these operations more quickly and more uniformly than by hand. To this end the invention in one aspect, provides a novel and compact machine which, as illustrated, comprises means for coating the inside counter portion of a shoe with adhesive, expansible members for pressing the lining against the adhesive-coated surface, and means for securing a shank piece in the shoe. While illustrated as especially adapted for performing the described operations, the several instrumentalities employed embody, in various features, broad novelty, and it is not the intention to limit the invention to the performance of these particular operations or to turned shoe manufacture. The novel features relating to the adhesive coating means are not however claimed herein, these features being claimed in a divisional application, Serial No. 232,330, filed November 10, 1927.

After the coating of adhesive has been applied to the inside of the shoe, and the lining has been turned right side out again, it is necessary that the lining be smoothly pressed against the coated surface. So far as I am aware, no mechanical means has previously been designed for applying outward pressure in this manner, such work always having been done by hand. In this aspect my invention contemplates the use of members to be inserted in a shoe, and means to open or expand them into engagement with the inside of the shoe, applying an outward pressure

thereagainst. Preferably, these members engage only a portion of the lining at any one time, and are given a bodily movement relatively to the shoe, to apply a progressive or "wiping" pressure, as by this arrangement all wrinkles and irregularities are smoothed out of the lining as it is pressed against the adhesive-coated inner surface of the shoe. A feature of the invention is to be found in the provision of means for closing or contracting these members or wipers, before their bodily withdrawal motion begins, to obviate possible displacement of the lining by an upward wiping action at the end of the cycle.

In order to prevent undue strain on the shoe during this operation, I provide a novel support for the outside of the shoe, illustrated as being yieldingly mounted on an arm which moves it to and from active position.

According to one form of the invention, the wiper head carries means to insert a shank piece, and may embody means, illustrated as staple-inserting mechanism, for fastening it in place.

These and other features of the invention, including details of construction and combinations of parts, will be apparent from the following description of the illustrative embodiment of the invention shown in the accompanying drawings, in which

Fig. 1 is a front elevation of the machine;

Fig. 2 is a detail view showing the work support for the staple inserting mechanism;

Fig. 3 is a side elevation of the machine;

Fig. 4 is an enlarged front elevation showing the head of the machine;

Fig. 5 is a section taken generally on the line 5—5 of Fig. 4 and showing the coating mechanism;

Fig. 6 is a section taken generally on the line 6—6 in Fig. 4 and showing the lining smoothing mechanism;

Figs. 7 and 8 are sections taken respectively on lines 7—7 and 8—8 in Fig. 6 and showing the lining smoothing wipers;

Fig. 9 is a section taken generally on the line 9—9 in Fig. 4 and showing the staple forming and inserting mechanism;

Fig. 10 is a section on the line 10—10 in Fig. 3 showing the actuating mechanism;

Figs. 11 and 12 are views of a turn shoe, partly broken away, showing the insertion of the counter and the coating with adhesive;

Fig. 13 is a perspective showing the relative positions of the sole, shank piece, and counter when assembled in a shoe;

Fig. 14 is a view similar to Fig. 7 but showing the wipers expanded inside of a shoe;

Fig. 15 is a detail view showing the stapling of the shank piece to the sole; and

Fig. 16 is a view generally similar to Figs. 6 and 9 showing a modification according to which the lining smoothing and staple inserting mechanisms are arranged for simultaneous operation.

The general organization of the machine comprises a base 20 supporting coating mechanism 100, lining smoothing mechanism 200, and staple forming and inserting mechanism 300. The machine is intended to operate on a shoe S (Fig. 11) which has just been turned, in which the lining L is pulled inside out and a molded counter C is inserted by hand. As shown in Fig. 12 the first step is the coating of the interior of the shoe with adhesive by the brush 102 of the coating mechanism 100. The second step comprises replacing the lining and smoothing it down against the adhesively coated counter portion of the shoe by the wipers 202 of the smoothing mechanism 200. After the smoothing of the lining a shank piece F (Fig. 13) is placed in the shoe over the inturned bottom margins of the lining and counter, and, as shown in Fig. 15, the last step is the insertion of a staple M to fasten the shank piece F to the sole T. Fig. 13 shows the relative positions in the finished shoe of the sole T, the counter C, and the shank piece F which is reinforced by a stiffener P and is fastened to the sole by a staple M.

According to the modification shown in Fig. 16 the lining smoothing mechanism and staple forming and inserting mechanism are mounted in one head. When this modification is used the shank piece is carried by prongs 400, and is placed in the shoe thereby at the time the lining is smoothed by the wipers 202. At the end of the lining smoothing movement the staple is inserted through the shank piece to fasten it to the shoe and wipers 202 and prongs 400 are then withdrawn from the shoe.

A motor 22 drives, through a belt 24, pulley 26, worm 28, and worm gear 32, the main drive shaft 30 which is intended to rotate constantly during the operation of the machine. Various cams and gears which operate the parts of the machine are mounted on the main shaft 30 and various levers and gears driven thereby are mounted on secondary shafts 34 and 36 (Fig. 10).

The coating mechanism 100 comprises a brush 102 carried by a shaft 104 which is mounted for both rotary and axial movement. The shaft 104 is rotated continuously during the operation of the machine by a train of gears 106, 108, 110, 112 and 114

(Figs. 5 and 10). Gear 106 is fixed on shaft 30 and the gear 114 is provided with a key or lug riding in keyway 116 of the shaft 104. By this arrangement the train of gears is continuously driven and shaft 104 is rotated by gear 114 in both raised and lowered positions. A sleeve 118 is secured to the shaft 104 in any desired and well-known way to permit rotation thereof and is arranged to be raised and lowered by a lever 120 acting through a pin-and-slot connection 122 to move the shaft 104 axially. The lever 120 is lowered by a coil spring 124 and is raised by a cam 126 acting against cam roll 128. Cam 126 is secured to a sleeve 130 which also carries a Horton clutch 132 arranged in the usual way to be secured to the continuously rotating shaft 30 or to be released therefrom by the engagement of abutments 134 and 136 with a pawl 138 mounted on a bell crank lever 140 operated by treadle rod 142 and treadle 144. A bracket 146 on the support 20 carries a reservoir 148 for the adhesive.

By the above arrangement of parts the brush 102 is continuously rotated and is controlled by treadle 144 to be raised axially out of the adhesive in the receptacle 148 by the first depression of treadle 144 and lowered again into the adhesive upon a second depression of this treadle. If preferred, the abutment 134 might be omitted on the Horton clutch in which case operation of the treadle 144 would result in axial movement of the shaft 104 to raise brush 102 out of the adhesive in receptacle 148 long enough to place a shoe thereover to coat the interior counter portion and to remove it again, after which the brush would automatically descend again into the adhesive.

The forward part of the shoe is protected from possible engagement with the brush 102 by a shield or support 150, as best shown in Fig. 12, which also acts as a gage to position the shoe.

The reservoir 148 is hermetically sealed by a cover 152, secured thereto by clamping nuts 158. A filling opening in this cover is normally sealed by a threaded cap 160. The central portion of the cover is formed into an inner receptacle 154, of somewhat larger diameter than brush 102, in the bottom of which are holes 156 communicating with the inside of reservoir 148. By this arrangement, when brush 102 is raised, adhesive flows from reservoir 148 into receptacle 154 up to the top of holes 156, at which height it is held by the pressure of the atmosphere. When brush 102 descends, it acts as a pump or piston, forcing the fresh supply of adhesive upward between the brush and the wall of receptacle 154, to all parts of the brush.

After the interior counter portion of a shoe has been coated with adhesive by the above described mechanism, as shown in Fig. 12, the lining L is folded down into place and is

smoothed against the adhesive coated surface by wipers 202. The mechanism indicated generally at 200 which actuates the wipers comprises a plunger 204 (Fig. 6) carrying a support 206 in the form of a plate to which wipers 202 are pivoted at 208. The plunger 204 is mounted for sliding movement in the head of the machine and is limited as to upward movement by engagement of lug 210 with the frame of the machine, and is yieldingly held against downward movement by engagement of lug 210 with a compression spring 212 whose tension may be adjusted by means of a set screw 214.

Inside of the plunger 204 is slidingly mounted a link 216 attached to the knuckle of a toggle 218 the ends of which engage lugs 220 on the wipers 202 to expand them when link 216 is depressed, thereby straightening the toggle 218. When the link 216 is raised a spring 222 acts to contract the wipers.

Threaded on the upper end of link 216 is a sleeve 224 which may be locked in any desired position by a lock nut 226 and which carries pins 228 embraced by slots in the forked end of a bell crank lever 230 mounted on the shaft 36. Bell crank lever 230 is rocked to pull upwardly on the link 216 by a spring 232 and is rocked to depress link 216 by a cam 234 acting against cam roll 236. The cam 234 is carried by a sleeve 238 which also carries a Horton clutch 240 controlled in the usual way by treadle rod 242 and treadle 244.

Also mounted on the sleeve 238 controlled by treadle 244 is a cam 246 engaging a cam roll 248 carried by lever 250 mounted on sleeve 252 on the shaft 34. The sleeve 252 carries an arm 254 which supports a cup 256 shaped to fit over the outside counter portion of a shoe and to provide support for the exterior side, rear and bottom surfaces of this portion of the shoe. The cup 256 is yieldingly connected to the arm 254 by plunger 258 and spring 260 and the position of the cup 256 may be adjusted by longitudinally moving the plunger 258 by means of a nut 262 threaded thereon.

At the conclusion of the downward stroke of plunger 204 it is locked by a pawl 264 having an integral lug 266 pressed by a spring 268. The lower end of this pawl snaps over the top of plunger 204 and holds it during the first part of the upward movement of link 216, thus contracting the wipers before they are bodily moved. When the bottom of a cutout portion 272 on link 216 cams against the rounded head of pawl 264, it forces the pawl back against the tension of spring 268, releasing plunger 204 which is then returned to upper position by spring 212. A setscrew 270 may if desired be provided to govern the tension of spring 268.

In the operation of this part of the machine the shoe is placed over the wipers 202 and the treadle 244 is depressed to cause sleeve 238 to be rotated through one revolution by the shaft

30. At the beginning of this rotation arms 250 and 254 are rocked about shaft 34 by the cam 246 to raise the cup 256 into position to fit over and support the outside counter portion of the shoe. Immediately thereafter the link 70 216 begins to descend straightening the toggle 218 and expanding wipers 202 as far as possible to place them against the lining of the shoe. When the wipers 202 have expanded as far as permitted by the shoe further downward motion of link 216 causes the ends of the toggle 218 to engage the plate 206 thereby forcing the wipers bodily downward in engagement with the lining and compressing the spring 212. The end of this stroke is 80 shown in Fig. 14.

The lining having been smoothed down as described, a shank piece F is inserted in the shoe to cover the shank and heel seat and the lower margins of the lining and the counter, 85 as will be apparent from Figs. 13 and 15. The shank piece F is secured in this position by a staple M which is formed and driven by the staple inserting mechanism shown in Figs. 9 and 10 and indicated generally by the 90 reference numeral 300. As staple inserting mechanism of this general character is well-known only a brief description of the various parts will be given. The staple is formed from a wire W fed from a spool 302 (Fig. 1) 95 by any suitable type of feeding mechanism operated by levers 304 and 306 operated by cam 308 on shaft 30. The wire is fed over an inside former 310 which is withdrawn after the formation of the staple by a bell crank 100 lever 312 operated by a face cam surface 314 on cam 308. The wire is formed about this inside former by an outside former of any suitable and well-known construction operated by arms 316 secured to a sleeve 318 on 105 shaft 34 to constitute a bell crank lever carrying a cam roll 320 also bearing against the cam surface 314. After the formation of a staple by the inside and outside formers, and the withdrawal of the inside former 310 by 110 its bell crank 312, the staple is driven by a plunger 322 depressed by an arm 324 which is swung downwardly by coil spring 326, as soon as the cam roll 328 carried thereby rides over the point 330 of cam 332 on shaft 30. 115

Cams 308 and 332 are mounted on a sleeve which also carries a Horton clutch 334 arranged to be secured to shaft 30 during one revolution by depression of treadle rod 336 by means of treadle 338. As shown in Figs. 120 1 and 2 there is attached to treadle rod 336, a bracket 340 secured to a lever 342 arranged to raise the work support 344 against the outside of the shoe to clinch the staple as shown in Fig. 15.

According to the modification illustrated in Fig. 16 the shank piece is placed on prongs 400 carried by the support 206 and the shank piece positioned in the shoe at the same time that the lining is smoothed down by wipers 202. 130

- At the end of this smoothing operation a staple is formed and driven to fasten the shank piece in place, whereupon the counter support or heel cup 256 is withdrawn and the shoe is removed. As the wiper operating mechanism and the staple forming and inserting mechanism illustrated in Fig. 16 are the same as above described, no further description thereof is deemed necessary. It will be noted that when this form of the apparatus is used one rotation of shaft 30 is sufficient to position a shank piece in a shoe, wipe down or smooth the lining, and staple the shank piece in place.
- It is believed that the operation of this machine will be understood without further explanation from the foregoing description. While the invention has been illustrated and described as embodied in a machine for operating on turned shoes, it will be appreciated that in various aspects it is capable of other uses and it is not the intention to limit its scope thereby or otherwise than by the terms of the appended claims.
- Having described my invention, what I claim as new and desire to secure by Letters Patent of the United States is:
1. A machine for operating on shoes comprising, in combination, means for smoothing the lining against the inside counter portion of a shoe and placing a shank piece in the shoe over the margin of the lining, and means to secure the shank piece in place.
  2. A machine for operating on lined articles comprising, in combination, means to smooth a lining against the inside of an article, and to place a piece of stock over the margin of the smoothed lining, and means to attach the piece of stock in place.
  3. A machine of the class described, comprising, in combination, a support for the outside of an article, means to rub concurrently against opposite sides of the interior of an article supported thereby and to place a piece of stock in the article, and means to attach the piece of stock in place.
  4. A machine of the class described comprising, in combination, expanding members to engage the interior of an article, a support for a piece of stock in advance of said members to place it in the article, and means to fasten the piece in place.
  5. A machine of the class described comprising, in combination, a support for the outer surface of an article, expanding members to engage the interior of an article supported thereby, a support for a piece of stock in advance of said members, and means to fasten the piece of stock in place in the article.
  6. A machine of the class described comprising, in combination, expanding wipers to smooth a lining, prongs to position a piece of stock over the margin of the smoothed

lining, and fastening-inserting means to attach the piece of stock. 65

7. A machine for use in making shoes comprising, in combination, a support shaped to fit over the outside of a shoe, a device to apply pressure to the lining of a shoe supported thereby, a carrier to insert a shank piece in the shoe, and means to attach the shank piece to the shoe. 70

8. A machine for use in making shoes comprising, in combination, expanding wipers to smooth the lining against the adhesive-coated counter of a shoe, prongs to insert a shank-piece in the shoe as the lining is smoothed, and a device to insert a metallic fastening to hold the shank piece. 75

9. A machine of the class described comprising, in combination, a support for the outside of an article, and means simultaneously to exert pressure at a plurality of points on the inside of an article supported thereby, to place a piece of stock therein, and to distribute the pressure progressively across a portion of the inside of the article. 85

10. A machine of the class described comprising, in combination, means progressively to exert pressure at opposed points on the inside of an article and to place a piece of stock therein, and means to fasten the article and the piece of stock together. 90

11. A machine of the class described comprising, in combination, means to smooth the body portion of a lining, and to press the lining against the inside of an article to which the lining is attached, and means to cover the margin of the lining. 95

12. A shoe machine comprising, in combination, means to smooth the lining of a shoe, and means to insert a shank piece in the shoe. 100

13. A shoe machine comprising, in combination, a device to insert a shank piece in a shoe, and means carried by said device to wipe down the lining of the shoe. 105

14. A shoe machine comprising, in combination, a support for the counter portion of a shoe, means to rub against the inside of the upper of a shoe supported thereby, and means to insert a shank piece. 110

15. A device comprising, in combination, a support, movable wipers on said support constructed and arranged to engage opposite sides of a piece of work, article-carrying means mounted on said support for cooperation with said wipers and means for positioning a fastener relatively to the article and applying the fastener to secure the article to the piece of work. 115

16. A device comprising, in combination, a support, movable wipers mounted thereon, article-carrying prongs on the support, and mechanism to expand and contract the wipers. 120

17. A machine of the class described com-

- prising, in combination, a support, movable wipers thereon, and means carried by the support and constructed and arranged to project a fastening outwardly from the interior of a 5 shoe.
18. A shoe machine comprising, in combination, wiping means to press the lining of a shoe outwardly against the counter, and means for inserting a fastening at the conclusion of the wiping operation. 10
19. A shoe machine comprising, in combination, means for placing a shank piece inside a turned shoe, and independent means for attaching said piece to the shoe. 15
20. A shoe machine comprising, in combination, means to position and support a shoe, a support for a shank piece constructed and arranged to engage the inside of a shoe to locate the shank piece in a definite location 20 inside the shoe, and means to force a metallic fastening through the shank piece into the shoe.
21. A shoe machine comprising, in combination, means to position a shank inside a turned shoe, and means to staple the shank to the shoe. 25
22. A shoe machine comprising, in combination, a picker head to place a piece of stock inside of a shoe and to engage a portion of the shoe to gauge the location of the piece relatively thereto, and fastening inserting means to attach the piece of stock to the inside of the shoe. 30
23. A machine of the class described comprising a support for the outside of a shoe, a device adapted to extend inside of a shoe engaged by said support, wiper members carried by said device for engaging the lining of the shoe, means on said device for engaging and holding a shank piece, and mechanism for effecting relative movement between said device and said support to smooth the lining and to position the shank piece in the shoe. 35
24. A shoe machine comprising, in combination, a support for the counter portion of a turned shoe, and means to position and staple a shank piece inside a shoe supported thereby. 40
25. A shoe machine comprising, in combination, a member to support a shoe by engagement with the outside of the upper at the heel, and expansible means to apply wiping pressure to the inside of a shoe supported thereby. 45
26. A shoe machine comprising, in combination, a support for a shoe, and means to rub across the inside of the lining to press the lining outwardly against the inside of the adhesive-coated counter of a shoe supported 50 by said support.
27. A machine of the class described comprising, in combination, a support to engage the outside of a hollow article, and an expansible wiper member progressively to apply 55 wiping pressure simultaneously to opposite sides of the interior of an article supported thereby.
28. A machine of the class described comprising, in combination, a support for the outside of an article, a member to engage the inside of an article supported thereby, and means to operate said member to apply outward pressure to the inside of the article and thereafter to move said member bodily with respect to the article progressively to rub the 60 inside of the article. 75
29. A shoe machine comprising, in combination, a support for the outside of a shoe, and means progressively to lay a lining against the inside of the counter of a shoe 70 supported thereby. 80
30. A shoe machine comprising, in combination, an expansible wiping device for engaging the inside of the counter portion of a shoe, a yieldingly mounted work support shaped and arranged to engage the exterior side, rear and bottom surfaces of the counter portion of the shoe, means for moving said support into position to co-operate with the wiping device yieldingly to engage the rear 85 of the counter portion and to support the sides and bottom thereof, and means for thereafter laterally expanding the wiping device into engagement with the sides of the counter portion and bodily moving said device toward 90 the bottom of the shoe progressively to smooth the lining. 95
31. A shoe machine comprising, in combination, expansible wipers to be inserted in a shoe, means to expand the wipers to engage the inside of the shoe and to move them to apply wiping pressure to the shoe, and means to hold the shoe stationary while it is being wiped. 100
32. A machine comprising, in combination, expansible wipers, means to expand the wipers to apply outward pressure and thereafter bodily to move the wipers to give them a wiping or rubbing motion, and a shoe support to receive the thrust of the wipers. 105
33. A shoe machine comprising, in combination, expansible wipers, constructed and arranged to project inside of a shoe to engage the shoe upper, means for supporting a shoe while it is being acted upon by the wipers, 110 a toggle to expand said wipers, and mechanism for moving the wipers toward the support after the wipers have been expanded. 115
34. A shoe machine comprising, in combination, members to be inserted in a shoe, means relatively to move said members to force them outwardly against the inside of the shoe and bodily to move the members while in engagement with the shoe, progressively to apply wiping pressure thereto, and a shoe support movable into and out of operative position. 120
35. A shoe machine comprising, in combination, a member shaped to fit over and support a portion of the outer surface of a shoe, 125

- members to engage the inside of the portion of the shoe so supported, and means relatively to move said members to press the shoe between them and the outer member, and to wipe said members over the inside of the shoe progressively heightwise of the shoe.
36. A shoe machine comprising, in combination, means to engage the lining of the upper upon the inside of a shoe, and mechanism to actuate said means to wipe the lining downwardly toward the shoe bottom.
37. A machine comprising, in combination, a movable support, wipers mounted thereon, a toggle engaging said wipers, a plunger on the support to engage the knuckle of the toggle to control the expansion and contraction of the wipers, and means for operating the wipers to rub a piece of work after the wipers have been expanded.
38. A machine comprising, in combination, a yieldingly mounted support, wipers mounted thereon, means to expand the wipers, and a member mounted on and movable relatively to the support to actuate said wiper-expanding means and thereafter to move the support while the wipers are expanded.
39. A shoe machine comprising, in combination, a member to support a shoe by engagement with the shoe bottom, a wiper movable relatively to said member to smooth the inside of a shoe supported thereby, and treadle-controlled mechanism to move said member into shoe-supporting position and thereafter to operate said wiper.
40. A shoe machine comprising, in combination, pressure applying members, means to expand said members and move them bodily while expanded to apply a progressive wiping pressure, and means to cause said members to be contracted before bodily withdrawing movement.
41. A shoe machine comprising, in combination, pressure applying members, a yieldingly mounted support therefor, a rod movable first to actuate said members and thereafter to move the support to cause said members to apply a progressive wiping pressure, and means to retain the support at the end of said movement until the members return to inactive position.
42. For use in a shoe machine, a counter support comprising, in combination, a cup to fit over and support the counter portion of a shoe, a plunger carrying said cup, an arm in which the plunger moves, and a yielding connection between the plunger and the arm.

43. A machine for operating on shoes comprising, in combination, means to support the sides of a shoe against lateral outward pressure, movable means progressively to apply pressure outwardly against the inside of a shoe supported thereby, and means for actuating said members to wipe a lining downwardly toward the shoe bottom.

44. A machine for operating on shoes having linings each attached along one margin and comprising, in combination, members to project inside of a shoe to engage the lining thereof near the attached margin, and means relatively to move said shoe and said members in engagement with the lining toward the free margin thereof, progressively to smooth the lining.

45. A machine for operating on shoes comprising, in combination, pressure-applying members to be inserted in a shoe, and means to separate said members and move them into engagement with opposite portions of the inside of the shoe and thereafter to move them in the direction of the height of the shoe progressively to apply wiping pressure thereto.

46. A machine for operating on shoes comprising, in combination, a normally contracted wiper device to engage the lining upon the inside of a shoe, and means to expand said device and thereafter to move it in the direction of the height of the shoe, to smooth the lining.

47. A machine for operating on sewed-seat turn shoes comprising, in combination, pivoted wipers to be inserted in a shoe, means to expand said wipers to engage the shoe lining near one margin, and an arm relatively to move the shoe and said wipers progressively to apply outward wiping pressure against the lining.

48. A machine as defined by claim 47, in which the sides of the shoe are supported against the outward pressure of the wipers.

49. A machine for operating on shoes comprising, in combination, means to apply outwardly-directed pressure to the inside of a shoe, means for engaging the bottom and the sides of the shoe and supporting the shoe against said pressure, and means relatively to move the first and second means to smooth the inside of the shoe.

In testimony whereof I have signed my name to this specification.

ARTHUR F. PYM.
